US00D817371S

(12) **United States Design Patent** (10) Patent No.: **US D817,371 S**
(45) Date of Patent: ** May 8, 2018

(54) **SPROCKET**(71) Applicant: **DEKA Products Limited Partnership**,
Manchester, NH (US)(72) Inventors: **Daniel S. Karol**, Southborough, MA
(US); **William D. Hunt**, Gilmanton,
NH (US); **Jason M. Overson**,
Manchester, NH (US)(73) Assignee: **DEKA Products Limited Partnership**,
Manchester, NH (US)(**) Term: **15 Years**(21) Appl. No.: **29/572,421**(22) Filed: **Jul. 27, 2016**(51) LOC (11) Cl. **15-99**

(52) U.S. Cl.

USPC ..... **D15/148**(58) **Field of Classification Search**USPC D12/123, 124, 126, 501, 507; D15/122,
D15/138, 143, 148, 149

CPC F16H 7/06; F16H 7/12

Primary Examiner — Melanie H Tung*Assistant Examiner* — Fitzgerald L Butac(74) *Attorney, Agent, or Firm* — Kathleen Chapman(57) **CLAIM**

The ornamental design of a sprocket, as shown and described.

DESCRIPTION

FIG. 1 is a front, top, right side perspective view of the sprocket, showing our new design;
FIG. 2 is a front side elevational view thereof;
FIG. 3 is a rear side elevational view thereof;
FIG. 4 is a left side elevational view thereof;
FIG. 5 is a right side elevational view thereof;
FIG. 6 is a top plan view thereof; and,
FIG. 7 is a bottom plan view thereof.
